UNITED STATES PATENT OFFICE.

PATRICK KEEGAN, OF FALL RIVER, MASSACHUSETTS.

FILLING-END-CLEARING MECHANISM FOR WEFT-REPLENISHING LOOMS.

Application filed April 23, 1924. Serial No. 708,550.

To all whom it may concern:

Be it known that I, PATRICK KEEGAN, a citizen of the United States, residing at Fall River, county of Bristol, State of Massachusetts, have invented a certain new and useful Improvement in Filling-End-Clearing Mechanism for Weft-Replenishing Looms, of which the following is a specification, reference being had therein to the accompanying drawings.

This invention relates to weft replenishing looms, and particularly to the mechanism for controlling the loose end of the weft or filling remaining on an exhausted bobbin or equivalent filling carrier when the latter is discharged from the shuttle by the weft replenishing mechanism, in order to prevent said loose end from being drawn into the cloth by the shuttle. The invention has for its general object to provide mechanism of this character which will operate to sweep the loose weft end away from the lay and securely clamp the same, said mechanism being universally adjustable to adapt the same to the requirements of any particular loom, being arranged to clamp the filling thread yieldingly so as to hold the same securely irrespective of its size, and having provision whereby the same is capable of yielding in order to avoid injury thereto in case of accidental obstruction as, for example, should a bobbin accidentally fall between the same and the lay.

The foregoing and other objects of the invention, together with means whereby the same may be carried into effect, will best be understood from the following description of one form or embodiment thereof illustrated in the accompanying drawings. It will be understood, however, that the particular construction described and shown has been chosen for illustrative purposes merely, and that the invention, as defined by the claims hereunto appended, may be otherwise practised without departure from the spirit and scope thereof.

In said drawings:

Fig. 1 is a front elevation, Fig. 2 a plan partly broken away, and Fig. 3 an end elevation of one end of the front of a loom having the invention applied thereto.

Fig. 4 is a detail section taken substantially on the line 4—4, Fig. 2.

Fig. 5 is an enlarged section taken substantially on the line 5—5, Figs. 1 and 2.

Figs. 6 and 7 are detail sections taken substantially on the lines 6—6, Fig. 3, showing the parts in different positions.

Fig. 8 is a detail plan view illustrating the adjustable mounting of the cam plate 60 on the lay.

The invention is herein shown as applied to a weft replenishing loom of well-known type. 15 denotes the breast beam constituting part of the frame and supported by end frame members one of which is shown at 16 in Fig. 3. 17 denotes the lay, 18 (Fig. 3) the shuttle, and 19 the picker stick. The bobbin magazine of the weft replenishing mechanism is indicated in dotted lines at 20, the bobbin transerrer at 21, the transferrer spring at 22 and the chute plate constituting the bobbin chute at 23. The breast beam rock shaft through which the weft replenishing mechanism is controlled by the feeler mechanism (not shown) is indicated at 24. The parts thus far referred to are not shown in full and will not be described in detail herein, since, except as hereinafter pointed out, and in so far as they enter into combination with other parts hereinafter described, they form no portion of the present invention and may be of any usual construction well known in the art.

Adjustably secured, as by bolts 25, to the breast beam 15, is a bracket 26 having a stem 27 extending substantially parallel to the breast beam and lay. Adjustably secured, as by set screws 28, to the stem 27, is the hub 29 of the upper section 290 of a hanger the lower section 291 of which is adjustably secured to said upper section by bolts 36 and 37. To the lower hanger section 291 is adjustably secured, as by a screw bolt 30, a guide 31. Mounted in the guide 31 for movement in a direction at right angles to the breast beam and lay, or in the direction of movement of the latter, is a slide 32 normally pressed toward the lay and held in the position shown in the drawings by a spring 33 (see particularly Fig. 5) surrounding a stem 34 projecting rearwardly from said slide and guided in an opening in a flange 35 on the guide 31. The spring 33 is interposed between the flange 35 and the rear end of the slide 32 the normal position of which, under the influence of said spring, is determined by the engagement of a shoulder formed by the forward end of the stem 34 with a shoulder 38 on the guide 31. The

mechanism for controlling the loose weft end is carried by the slide 32 and is therefore yieldingly mounted on the frame, so as to avoid injury to said mechanism should 5 any obstruction, such as a bobbin, accidentally find its way between the same and the lay.

Rigidly secured to or formed integral with the slide 32 is a horizontal holder plate 39 having associated therewith a second, 10 spaced, parallel holder plate 40. Said plates are separated by a spacing block 41 (see particularly Fig. 4) and are connected at their ends by studs 42 and 43 provided with springs 44 (see also Fig. 5) and 45, whereby 15 said plates are yieldingly pressed toward one another to an extent permitted by the spacing block 41. The holder plates 39 and 40 are disposed at an angle to the lay, said plates having their rear ends closely adjacent 20 the lay when the latter is in its foremost position, as shown in Fig. 2, and diverging therefrom so as to leave between the same and the bobbin chute 23 sufficient space for the discharge of an exhausted 25 bobbin 46.

Pivoted on the stud 42 between the holder plates 39 and 40 is a bell crank 14 one arm 47 of which normally occupies a position between said plates but is adapted to be 30 swung out of its normal position into the position shown in dotted lines in Fig. 2, in which its end is received in a slot 48 in the bobbin chute 23. Mechanism (hereinafter described) is provided whereby, when the 35 weft replenishing mechanism is rendered operative, under the control of the rock shaft 24, to discharge an exhausted bobbin, the arm 47 is, as the lay moves forwardly, swung into the position shown in dotted 40 lines in Fig. 2, thereby permitting the exhausted bobbin 46 to drop in front of said arm. Thereafter, as the lay starts to move rearwardly, the arm 47 is swung forwardly away from the lay across the bobbin chute, 45 sweeping the weft 49 of the discharged bobbin away from the shuttle, and clamping the same between said arm and the holder plates 39 and 40. It will be observed that this weft engaging movement of the arm 47 is away from the lay and shuttle, thereby 50 removing the loose weft end from the latter and securely clamping the same, so as to avoid any possibility of its being drawn into the cloth by the shuttle. By reason of the 55 yielding mounting of the holder plates 39 and 40, the weft is securely clamped irrespective of its size.

The other arm 50 of the bell crank 14 has pivotally connected thereto a rod 51 guided 60 in an opening in a bracket 52 projecting from the holder plate 39. A spring 53 surrounds the rod 51 and is interposed between the bracket 52 and a collar 54 on said rod, 65 said spring tending normally to hold the arm 47 in its clamping position between the

holder plates 39 and 40, and contributing to the yielding clamping action of the parts. The arm 50 is formed at its end with a boss or hub 55 in which is guided a vertically sliding stud 56 having a head 57 between 70 which and the upper end of the hub 55 is interposed a spring 58 tending normally to hold said stud in the elevated position shown in Fig. 6. The head 57 of the stud 56 is engaged by the rear end of a lever 59 75 pivoted at 60 to the hanger section 291, said rear end being limited as to its upward movement by a stop 61 carried by the guide 31. The lever 59 is formed with a cam-shaped forward end 62 which is engaged by 80 an angularly offset arm 63 on a rod 64. The rod 64 is adjustably secured, as by set screws 65, in the hollow end 66 of a crank 67 having a hub 68 adjustably connected with the end of the breast beam rock shaft 24 by a 85 coupling sleeve 69 and set screws 69. The lay 17 is provided with a forwardly extending lug 70 (see Figs. 6, 7 and 8) to which is secured, by means of a bolt 71, a cam plate 72. The lug 70 and cam plate 72 are formed 90 with slots through which the bolt 71 passes, said slots being disposed at right angles to one another, thereby permitting the cam plate 72 a substantially universal adjustment in a horizontal plane. When the stud 56 is in its normal position, as shown in Fig. 95 6, it is out of the path of movement of the cam plate 72, but when the lever 59 is rocked on its pivot, it will depress said stud into the position shown in Fig. 7, so as to cause 100 said stud to be engaged by the cam plate 72 when the lay moves forward. The stud 56 and cam plate 72 are formed with inter-engaging shoulders 73 and 74, whereby 105 when said stud is engaged by said cam plate, it will be held in depressed position until disengaged thereby by the rearward movement of the lay irrespective of the position of the lever 59.

During the normal operation of the loom, 110 the stud 56 occupies the inoperative position shown in Fig. 6, and the arm 47 is held by the spring 53 between the holder plates 39 and 40. When the controller shaft 24 of the weft replenishing mechanism is rocked by 115 the feeler mechanism preparatory to the discharge of an exhausted bobbin from the shuttle and the substitution of a filled one, as will be familiar to those skilled in the art, the angular arm 63 on the rod 64, by 120 engagement with the end 62 of the lever 59, rocks the latter on its pivot, thereby depressing the stud 56 into the position shown in Fig. 7. When the lay moves forward, the stud 56 is engaged on the cam 72, and the bell crank 14 is rocked, moving the arm 47 125 into the position shown by dotted lines in Fig. 2. The transerrer then operates, in the usual manner, to discharge the exhausted bobbin 46 from the shuttle and lay, 130

and said bobbin falls down the bobbin chute in front of the arm 47. As the lay moves rearwardly, the stud 56 is disengaged by the cam plate 72, permitting the spring 53 to sweep the arm 47 forwardly across the bobbin chute, carrying the loose weft end 49 away from the lay and clamping the same between the holder plates 39 and 40.

In order to prevent the weft end from slipping from the end of the arm 47 as the latter is swung forwardly, there is provided a curved guide 75 the rear end of which is secured to the lay or, preferably, to the bobbin chute plate 23 which in turn is secured to the lay, said guide engaging the weft and preventing movement thereof along the arm 47 to a sufficient extent to slip from the end of the latter. It will be observed that the angular position of the holder plates 39 and 40 and the curved form of the guide 75 provide ample space in front of the chute plate 23 for the downward passage of the discharged bobbin in front of the arm 47 when the latter is in the position shown in dotted lines in Fig. 2.

In order to prevent the collection of waste on the arm 47, the latter is preferably of a tapered form which tends to throw off the waste rather than to retain the same, 30 the guide 75, which is preferably located above the path of the said arm, preventing the weft from being thrown therefrom, as above explained.

Having thus described my invention, I 35 claim:

1. In a weft replenishing loom, in combination with the lay and the weft replenishing mechanism, of mechanism for removing the weft of a discharged bobbin from the lay 40 and clamping the same, said mechanism including a pair of spaced holder plates, a weft engaging arm, a spring for moving said arm between said plates to clamp the weft, and means operated by the lay and controlled by the replenishing mechanism 45 to move said arm away from said plates.

2. In a loom, the combination with the lay and the weft replenishing mechanism, of mechanism for removing the weft of a discharged bobbin from the lay and clamping the same, said mechanism including a pair of spaced holder plates, means for yieldingly forcing said plates toward one another, and an arm, movable between said plates to 55 clamp the weft.

3. In a loom, the combination with the lay and the weft replenishing mechanism, of mechanism for removing the weft of a discharged bobbin from the lay and clamping the same, said mechanism including a pair of holder plates, a spacing member between said plates, springs co-operating with the ends of said plates to force the same to-

ward one another, and an arm movable between said plates to clamp the weft. 65

4. In a weft replenishing loom, the combination with the breast beam, the lay, the shuttle, and the weft replenishing mechanism, of a bracket carried by the breast beam, a slide guided on said bracket for movement in the direction of movement of the lay, a spring for forcing said slide toward the lay, co-operating shoulders on said bracket and slide for limiting the movement of the latter toward the lay, and mechanism 75 carried by said slide and operated by the lay for removing the weft of a discharged bobbin from the shuttle.

5. In a weft replenishing loom, the combination with the lay, the shuttle, and the weft replenishing mechanism, of means for removing the weft of a discharged bobbin from the shuttle, a cam plate on the lay, a movable stud through which said weft-removing means is operated by said cam plate, and means controlled by said weft replenishing mechanism for moving said stud into the path of movement of said cam plate. 80

6. In a weft replenishing loom, the combination with the lay, the shuttle, the weft replenishing mechanism, and the bobbin chute through which the exhausted bobbins are discharged by said replenishing mechanism, of a bell crank having an arm movable across said chute to remove the weft of a discharged bobbin from the shuttle, a cam plate on the lay, a stud slidably mounted on the other arm of said bell crank, and means controlled by the weft replenishing 95 mechanism for moving said stud into the path of movement of said cam plate. 100

7. In a weft replenishing loom, the combination with the lay, the shuttle, and the weft replenishing mechanism including the feeler controlled rock shaft, of means operated by the lay for removing the weft of a discharged bobbin from the shuttle, means for operatively connecting said weft-removing means with said lay, a lever for operating 110 said connecting means, and an arm on the rock shaft for operating said lever.

8. In a weft replenishing loom, the combination with the lay, the shuttle, and the weft replenishing mechanism including the feeler controlled rock shaft, of means for removing the weft of a discharged bobbin from the shuttle, a cam plate on the lay, a movable stud through which said weft removing means is operated by said cam plate, 115 a lever for operating said stud, and an arm on the rock shaft for operating said lever. 120

In testimony whereof I affix my signature.

PATRICK KEEGAN.
